LIQUID MEASURING DEVICE

Emil E. Hageline, Chicago, Ill., assignor to The
Lathrop-Paulson Company, Chicago, Ill., a corporation of Illinois

Application February 8, 1943, Serial No. 475,101

3 Claims. (Cl. 222—445)

1

This invention relates to can washing apparatus, and more particularly to equipment for dispensing fluids adapted for use in apparatus for the washing of cans and the like.

An object of the invention is to provide apparatus for delivering a measured quantity of a treating fluid to a can and for carrying out such deliveries substantially instantaneously at predetermined time intervals or when a can reaches a predetermined position within the apparatus.

Another object of the invention is to provide apparatus for thoroughly mixing a treating fluid and a vehicle, such as steam, for introduction into the can. Still another object is to provide for the thorough distribution of the treating fluid and the steam vehicle throughout and over the entire inner surface of the can.

Another object of the invention is to provide means for accurately controlling the delivery of the small quantities of a treating fluid to the can which is to be washed. Yet another object is to provide mechanism for accurately measuring and regulating the quantity of treating fluid which is delivered in each operation. A further object is to provide means for visible control of the apparatus by the operator whereby the operator can readily and easily determine, regulate, and control the use of the treating solution.

In the use of a treating fluid, such, for example, as an acid cleaner in the washing of cans, only a small quantity of the treating fluid is introduced into each can. It is sometimes difficult in such an operation to thoroughly mix the treating fluid with a vehicle, such as steam, and to obtain a thorough distribution of the mixture over the surface of the can which is to be washed. The accurate control and regulation of the quantity of the treating fluid which is introduced into each can also presents many problems and difficulties. The present invention is designed to eliminate and obviate these difficulties and problems.

The invention is illustrated in the accompanying drawing in which Fig. 1 is a plan view of the apparatus; Fig. 2 is a side elevational view of the same apparatus; Fig. 3 is a fragmentary end view of the mechanism for actuating the valves; and Fig. 4 is a fragmentary side elevational view taken from the inside and showing the valve-actuating mechanism.

In the embodiment of the invention described herein, a nozzle 10 is disposed within the frame of the can washing machine and located in a position between the rails of the machine on which the can is supported in inverted position. The

2

apparatus for supporting and conveying the cans may be of any suitable or conventional construction. For example, the apparatus described and set forth in Otto B. Rufus application Serial No. 361,117, filed October 14, 1940, now Patent No. 2,437,757, March 16, 1948, for Can treating device, may be used for this purpose.

In can washing machines of the type illustrated in the Rufus application, the can is supported in inverted position upon a pair of spaced rails and is advanced along the rails by a suitable conveying mechanism. The can which is equipped with a central aperture is advanced to a position above the nozzle 10 so that steam or other gas and the fluid ejected from the nozzle 10 pass into the can to wash the inner surfaces thereof. This general type of equipment is well known and will not be described further in detail herein.

20 The nozzle 10 is connected to a conduit 11 for delivering the treating fluid, such as the acid cleaner, to the nozzle. A conduit 12 which communicates with the lower portion of the nozzle through a fitting 13 serves to introduce steam under pressure to the nozzle. Instead of steam,

25 any other suitable vehicle may be used to distribute the treating fluid throughout the inner surface of the can. However, steam is preferred for this purpose since the steam effects a sterilizing and cleaning action in itself and at the same time serves as a suitable vehicle for distributing the treating fluid.

30 The nozzle 10 is preferably so constructed that the steam introduced under pressure through the fitting 13 creates a vacuum within the nozzle adjacent the opening to the conduit 11 and, by reason of this vacuum, draws the treating fluid from the conduit 11 into the nozzle 10. The treating fluid from the conduit 11 and the steam from the fitting 13 mix in the nozzle and the mixture is ejected into the interior of the can.

35 The apparatus includes mechanism A for controlling the flow of steam into the nozzle 10, and mechanism B for regulating and controlling the flow of the treating fluid through the conduit 11 into the nozzle 10. The mechanisms A and B are synchronized so that the treating fluid may pass through the conduit 11 to the nozzle 10 when the steam passes through the conduit 12 to the nozzle 10.

40 The mechanism B for controlling and regulating the flow of treating fluid through the conduit 11 is mounted on a panel 14, which in turn may be supported on the frame member 15. A shaft 16, 45 supported in any suitable manner, is mounted for

longitudinal reciprocating movement and is connected to suitable means (not shown) for actuating the shaft 16 at periodic intervals. The actuating means for the shaft 16 may be so arranged as to cause the shaft to move rearwardly toward the mechanism A and to remain in rearward position for a short interval of time. The shaft is then moved forwardly toward the mechanism B and is quickly returned to rearward position. A collar 17, carried by the shaft 16, is pivotally connected at 18 to the link 19, which in turn is pivotally mounted at 20 on the frame 15. The rod 21, connected to the pivot 18, extends forwardly through the panel 14 and is equipped at its end with an enlarged head 22.

The rod 21 may be threaded at the end portion 49 thereof, and a nut 50 secured to the end portion 49 of the rod may be fixedly attached to the pivot 18 by welding or other suitable means. Thus, when the pivot shifts forwardly or rearwardly, the rod is reciprocated.

A valve 23, provided with a plunger 24, is disposed adjacent the head 22 on the rod 21. The valve 23 is of a conventional type whereina the movement of the plunger 24 controls the flow of fluid through the valve. When the plunger 24 is pressed inwardly toward the valve, the valve is opened and fluid flows therethrough, while when the plunger 24 moves outwardly to the position shown in Fig. 2, the valve is closed. The head 22 of the rod 21 is adapted to be brought into engagement with the plunger 24 of the valve 23 to open the valve and permit fluid to flow therethrough into the fitting 25 and thence to the conduit 11.

Mounted above the valve 23 is a graduated tubular container 26 of a transparent material, such as a transparent plastic or glass. As an example of the transparent plastic which may be used for this purpose, the material known as "Lucite," manufactured by E. I. duPont de Nemours Company, may be used.

The treating fluid flows into the container 26 from a valve 27 of the same type as valve 23 and having a plunger 28 adapted to be actuated by the head 29 of the rod 30. The rod 30 is secured by the pivot 31 to the lever 32 which is pivotally mounted at 33 on the frame 15. The lower end of the lever 32 extends downwardly in closely-adjacent relation to the shaft 16 and may be actuated by suitable means carried by the shaft 16.

The shaft 16, as illustrated, may be equipped with collars 51 and 52 which are rotatably mounted on the shaft 16 and carry a member 53 extending downwardly therefrom. An arm 34 extends laterally from the upper portion of the member 53 and is swingable upwardly and downwardly when the collars 51 and 52 rotate about the shaft 16, as seen particularly in Fig. 3. A member 54 is movable upwardly and downwardly, and the end pin 55 of the member 54 is adapted to engage the arm 34 to move the same upwardly when a can is passed beyond a predetermined position on the rails of the mechanism. Any suitable means for actuating the pin 54 may be provided.

When the arm 34 is in upper position, as indicated in solid lines in Fig. 3, rearward movement of the shaft 16 causes the arm 34 to engage the lower end of the lever 32 and urge the rod 30 and the head thereof forwardly into engagement with the plunger 28 to open the valve 27. When the valve 27 is opened, the treating fluid flows therethrough into the graduated container 26.

The treating fluid may be placed in a container 35 communicating at its lower end with an

outlet conduit 36 which communicates with the valve 37. The valve 37 is manually operable by means of the handle 38. A fitting 39 connects the valve 37 with the valve 27.

The rods 21 and 30 and the mechanism for actuating these rods are so arranged that the rod 30 is advanced and the valve 27 opened while the rod 21 is withdrawn and the valve 23 closed. Similarly, when the rod 21 is advanced and the valve 23 opened, the rod 30 is withdrawn and the valve 27 is closed.

The mechanism A for controlling the flow of steam into the conduit 12 includes a pair of ring members or collars 40 and 41 which are pivotally mounted on the shaft 16 and support a member 42 therebelow. The member 42 carries a head 43 which is adapted to engage the plunger 44 of the valve 45 to open and close the valve 45.

The member 42 is adapted to be swung into alignment with the plunger 44 of the valve 45 when a can is in position above the nozzle 10 and suitable mechanism may be provided for swinging the member 42 to this position of alignment. When the can is in position above the nozzle 10 and the member 42 is in alignment with the plunger 44 of the valve 45, the forward movement of the shaft 16 brings the head 43 on the member 42 into engagement with the plunger 44 and opens the valve 45. Steam, which is introduced through the conduit 46, flows through the valve 45 through the conduit 47 to the conduit 12 and thence into the nozzle 10. At the same time, the forward movement of the shaft 16 moves the rod 21 forwardly and brings the head 22 into engagement with the plunger 24 of the valve 23, thus opening the valve 23.

In operation, the treating fluid is placed in the storage tank or container 35 and steam under pressure is introduced into the conduit 46. The mechanism for actuating the shaft 16 is then set in operation and the shaft 16 moves rearwardly to close the valve 23 and open the valve 27, the valve 45 also being closed. The treating fluid then flows from the container 35 through the conduit 36, valve 37, fitting 39, and valve 27 to the transparent graduated container 26. As the fluid flows into the graduated container 26, the quantity of fluid received therein is visible to the operator of the machine. Since the valve 23 is closed, the fluid accumulates in the graduated container 26. The valve 27 remains open for a predetermined interval of time and adjustment of the valve 37 by the handle 38 allows regulation of the quantity of fluid delivered to the container 26. After a predetermined interval of time, the shaft 16 moves forwardly and the valve 27 is closed and the valve 23 is opened. At the same time, the forward movement of the shaft 16 causes the head 43 of the member 42 to be brought into engagement with the plunger 44 of the valve 45 and the valve 45 is opened to permit the flow of steam under pressure through the conduit 12 and into the nozzle 10. The steam passing through the conduit 12 and into the nozzle 10 draws the treating fluid from the container 26 through the open valve 23 and conduit 11 into the nozzle 10.

The flow of treating fluid from the container 26 through the conduit 11 into the nozzle 10 is substantially instantaneous so that when the valves 23 and 45 are opened, the steam is immediately ejected from the nozzle 10 and carries with it the treating fluid from the container 26. The treating fluid is thoroughly mixed with the steam and the steam mixture is distributed over the entire inner surface of the can.

By adjusting the flow of treating fluid through the valve 37, it is possible to control the quantity of treating fluid which is delivered to the container 26 in each time interval. As the treating fluid in the container 35 is gradually exhausted, the head of pressure upon the fluid becomes less and the flow of fluid through the valve 37 is decreased. Accordingly, the valve 37 may be adjusted to compensate for this change in flow so as to maintain constant the quantity of treating fluid which is delivered to the container 26. The visibility of the container 26 also permits the operator to determine roughly the concentration of the treating solution when the solution is colored and to determine by the rate of flow through the valve 37 the approximate quantity of solution remaining in the storage tank 35.

The speed with which the treating fluid is drawn through the fitting 25 and conduit 11 tends to prevent any clogging of the conduits.

Although the invention has been described in connection with can washing machines and with reference to a specific illustration, it will be apparent that changes and modifications may be made without departing from the spirit and scope of the invention.

I claim:

1. In can treating apparatus, a container for receiving treating fluid, means for introducing said fluid into said container at a predetermined rate, valve means for changing the rate at which said fluid is introduced by said means, means for automatically operating said introducing means during periodic intervals of substantially equal lengths whereby a measured quantity of said liquid is introduced into said container during each of said intervals, an outlet conduit extending downwardly from the lower portion of said container for the withdrawal of fluid therefrom, valve means in said conduit controlling the withdrawal of liquid through said outlet conduit, and means for automatically closing said last-

mentioned valve means when liquid is being introduced into said container and for opening said last-mentioned valve means when said measured quantity of liquid has been introduced into the container.

- 5 2. In can washing apparatus, a substantially transparent container for receiving treating fluid, said container being equipped with spaced graduations thereon, means for introducing fluid into 10 said container at a predetermined rate, valve means for controlling the rate at which fluid is introduced by said means, means for automatically operating said introducing means during periodic intervals of substantially equal lengths whereby a measured quantity of liquid is introduced into said container through each of said intervals, an outlet conduit for withdrawing fluid from said container, valve means in said outlet conduit for controlling the flow of fluid therethrough, and means for automatically operating the outlet valve means to close the same when liquid is being introduced into the container and to open the same when said measured quantity of liquid has been introduced into the container.
